Primary Examiner — T. Chase Nelson(74) *Attorney, Agent, or Firm* — Andrew F. Young, Esq.; Lackenbach Siegel, LLP(57) **CLAIM**

The ornamental design for a shoe sole, as shown and described.

DESCRIPTION

FIG. 1 is a front perspective view of the embodiment of the present invention.

FIG. 2 is a front elevation view of the embodiment shown in FIG. 1.

FIG. 3 is a rear side elevation view of the embodiment shown in FIG. 1.

FIG. 4 is a top plan view of the embodiment shown in FIG. 1.

FIG. 5 is a bottom plan view of the embodiment shown in FIG. 1.

FIG. 6 is a left side elevation view of the embodiment shown in FIG. 1; and,

FIG. 7 is a right side elevation view of the embodiment shown in FIG. 1.

No claim is made to the dashed line regions on the shoe sole or tread outside the disclaimed break-lines (dash-dot-dot-dash), nor is any claim made to the shoe upper as the dashed lines indicate disclaimed portions forming no part of the claimed design.
